(57) **CLAIM**

The ornamental design for a pillow core, as shown and described.

DESCRIPTION

FIG. 1 is a perspective view of a pillow core design showing my new design.

FIG. 2 is a front view of a pillow core.

FIG. 3 is a rear view of a pillow core.

FIG. 4 is a left side view of a pillow core.

FIG. 5 is a right side view of a pillow core.

FIG. 6 is a top view of a pillow core; and,

FIG. 7 is a bottom view of a pillow core.

Any contour shading is utilized to illustrate the surface contours of the pillow core design in the drawings and not to show surface pattern.

1 Claim, 7 Drawing Sheets
